UNITED STATES PATENT OFFICE.

JOHN GEORGE FORSTER, OF CHICAGO, ILLINOIS, ASSIGNOR TO OGLE CONSTRUCTION CO., OF CHICAGO, ILLINOIS, A CORPORATION OF ILLINOIS.

HOISTING MECHANISM AND CONTROL THEREFOR.

Application filed July 2, 1925. Serial No. 41,057.

This invention relates to a hoisting mechanism and a control therefor and contemplates the use of two spaced hoisting towers, one for handling coal, and the other for handling ashes, the buckets of which are alternately raised and lowered by the operation of a single or coaxial drums and which are balanced against each other, in connection with an electric control system which is not susceptible of being put in operation from the ash tower unless the coal loading mechanism in the coal tower is disabled, and which is automatically disabled when the coal bucket reaches the top of its tower.

15 The invention comprises the novel structure and combinations hereinafter described and more particularly pointed out and defined in the appended claims.

20 In the accompanying drawings, which illustrate a preferred form of this invention and in which similar reference numerals refer to similar features in the different views:

25 Figure 1 is a top plan view of a coal handling tower and an ash handling tower with a power house shown in section there-between, and a pair of railroad tracks;

30 Figure 2 is a side elevational view of the towers and power house;

35 Figure 3 is an enlarged and broken part elevational and part sectional view of the coal hoisting tower;

40 Figure 4 is a diagrammatic view of a D. C. electrical control system used in connection with the apparatus;

45 Figure 5 is a part elevational and part sectional transverse view of the ash hoist illustrating its use in connection with a railroad system;

50 Figure 6 is a part elevational and part sectional transverse view of the coal hoisting tower illustrating its use in connection with a railroad;

55 Figure 7 is an enlarged elevational view of the disabling mechanism for the coal loader;

60 Figure 8 is a diagrammatic view of an A. C. control system which may be used instead of the D. C. system, and

65 Figure 9 is a part elevational and part sectional view of a coal hoisting tower equipped with a coal storage bin.

70 Referring to Figures 1 and 2 of the drawings, there is shown a coal hoisting tower 1 and an ash hoisting tower 2. A power

house 3 is situated between them and a pair of parallel railroad tracks 4 are shown adjacent the towers for unloading ashes and loading coal. Each tower supports a drum or pulley 5 at its upper end over which cables 6 and 7 are respectively trained. One end of the cable 6 depends in the tower 2 and supports an ash bucket 8 (Figure 5). From the drum 5, the other cable 6 depends along the tower and is trained under a guide roll 9. From the guide roll 9, the cable 6 extends into the power house 3 and is attached to an operating drum 10.

75 One end of the cable 7 depends in the coal tower 1 and supports a coal bucket 11. The other end of the cable 7 is brought down from the drum 5 and under a guide roll 9 and attached to a drum 12 coaxially attached with the drum 10, but of larger diameter for a purpose that will later appear. The coaxial drums 10 and 12 are suitably geared to a motor 13 in the power house. It will be noted that both cables 6 and 7 extend over the tops of their respective drums. Consequently, when the drums rotate, one 80 cable will be wound up and the other will unwind, and one bucket will be lowered while the other will be raised. Consequently, one bucket will counterbalance the other. If it is desired that one bucket shall 85 travel empty, it may be filled with a suitable weight for counterbalancing purposes.

90 In referring to Figure 5, which is a view taken transversely of the track and which illustrates the ash tower, it will be noted that the engine is in position to dump its ashes into the ash pit. When the ashes are dumped into the pit, the ash bucket will, of course, be at the bottom of the pit to receive the ashes. The filled bucket is then elevated 95 and dumped into a hopper 14 provided with a chute 15 for conveying the ashes to an ash car.

100 In Figure 6 is shown the coal hoist receiving coal from a coal car 16, which discharges the same into the coal hopper 17. The coal bucket 11 in this tower in descending strikes a bar 18 (Figure 3) which is connected by a link 19 with a lever 20. The bar 18 is held in a suitable guide 18^a, and 105 as it descends, the lever 20 serves to lower the apron 21 of the coal chute 22 leading from the hopper 17, whereby the coal in the chute 22 will fall in the bucket. During this operation, the hopper is shut off from 110

the coal chute 22, since the downward movement of the apron 19 will rotate a valve mechanism for closing the port 23 between the hopper 17 and chute 22. It will be noted that the coal apron 21 extends over the bucket when the latter is in the bottom of the coal loading pit. Consequently, when the bucket is raised, it will lift the apron 21 toward closing position. A counter weight 20^a connected to the lever 20 will complete the closing movements of the apron. While the apron is being swung to closed position, the valve of port 23 is being opened. This loader mechanism does not constitute a part of this invention except in so far as it cooperates therewith, since it is but a slightly modified form of the loader mechanism shown in the Ogle Patent, No. 1,112,084. It merely differs from the mechanism of the patent in a different manner of closing the apron and elevating the bar 18, and in pivotally mounting the guide bar 18^a upon a pivot 24, as shown in Figures 3 and 7.

By pivoting the guide bar 18^a at its lower end, it may be swung to shift the loader bar 18 out of the path of the descending bucket. For this purpose, a pair of toggle links 25 are pivoted together at their inner ends. The outer end of one link is connected to the pivoted guide 18^a while the outer end of the other link is pivoted to a stationary post 26. A link 27 is connected to the joint of the toggle links 25 and extends to a suitable point in the tower 1. The upper end of the link 27 is connected to a lever 28 which is pivoted intermediate its ends to the tower. A link 29 (Figure 3) suspends from the lever 28 and controls the movable element 30 of a protective switch in the control circuit, which will be later described. It should merely be understood at the present time that when the lever 28 is manually swung upwardly by the operator, the toggle links 25 will flex downwardly, as shown in Figure 6, whereby the guide 18^a is swung upon its pivot to remove the loader bar 18 from the path of the descending bucket for disabling the loader mechanism. When the lever 28 is thuswise elevated, the switch member 30 will be moved to closed position. The purpose of disabling the coal loading mechanism is to prevent coal from being hoisted when ashes are being handled in the ash tower and there is no car present to receive the coal.

As the coal is raised in the bucket, it is dumped into a coal hopper 31 from which the coal is conveyed to the engine by a chute 32. If desirable, the hopper may be enlarged for storing a quantity of coal, and in Figure 9 I have illustrated a coaling tower having an addition 33 to the hopper 31. Coal may be stored in the hopper, which usually has a valve communicating with the

chute 32, when no engine is present for coaling purposes.

When such a storage hopper or bin is used, it is necessary that the coal bucket be raised higher than the ash bucket. For this reason, the drum for the cable on the coal bucket may be made a little larger, as previously explained. After the ash bucket has been raised, and its contents dumped into an ash car, it is usually lowered again into the ash pit. Usually one load of ashes will be all that is required to be hoisted. It is desired to automatically cut out the motor at such time. To accomplish this purpose a counterweighted limit switch 34 (Figure 3) is positioned in the motor circuit adjacent the upper end of the tower and when the coal bucket reaches the top of the tower, it actuates the switch 34 and opens the motor circuit.

In Figures 4 and 8 are shown, in diagrammatic form, control circuits for the connected ash and coal hoists. The control shown in Figure 4 is for a D. C. current, while that in Figure 8 is for an A. C. current. However, the general description of one will explain the other. In Figure 4 there is shown a three wire D. C. control system involving a starting circuit and a stop circuit. In referring to said figure, it will be noted that there is illustrated a relay and dynamic braking box 35 to which the supply wires 36 and 37 lead from a suitable source of electrical power. The wire 36 connects with a resistance or relay coil 38, the ends of which respectively attract the pivoted switch elements 39 and 40, the former making a connection with the wire 36. The wire 37 is connected to one of the motor feed wires 41. The other motor feed wire is connected to the switch element 39.

The starting circuit comprises a conductor 43 leading from the connection between the wires 37 and 41, to a starting switch 44, a conductor 45 leading from the starting switch 44 to the protective switch 30, and a return wire 46 leading from the protective switch 30 to the coil 38 and adapted to be put in electrical connection with the switch 40.

The stop circuit comprises a conductor 47 leading from the switch 40 and extending to the top of the coal tower, where it is connected to the limit switch 34, and a return wire 48 leading from the limit switch 34 to a stop switch 49 which is also connected with the conductor 43. A number of emergency stop switches 51 may be placed in the conductor 48.

A tumbler switch 51^a is shunted across the conductors 43, 46 and 47. This switch may be used to cut out the control system.

The starting circuit above described also has a shunt circuit comprising a conductor 52 leading from the wire 46 to a starting

switch 53 which is electrically connected to the wire 47 by a conductor 54, which also leads to a shunt switch 55 which is connected to the wire 48 by a conductor 56.

8 This shunt circuit cuts out the limit switch 34, so that the motor can be operated when the said switch is open.

In the operation of the apparatus, it will be assumed that the ash bucket 8 is at the

10 bottom of the pit ready to be hoisted, with the motor standing still. The starting switch 44 controls the motor for hoisting ashes; the closing of the switch 44, however, will not start the motor as long as the

15 protective switch 30 is open. The closing of the switch 30 will, of course, render inoperative or disable the loader mechanism. After the switch 30 has been closed, the

20 starting switch 44 will be momentarily closed for completing the circuit through the supply wires 36 and 37. The relay coil 38 will be energized for attracting the member 39 and closing the relay switch to the

25 motor. At the same time, the switch member 40 will be attracted for closing the circuit through the limit switch 34. When the operator releases the starting switch 44, it will, of course, spring to open position.

The operation of the motor will rotate the 30 winding drums for hoisting the ash bucket and lowering the coal bucket. After the ash bucket has been hoisted and dumped, the hoist will reverse and the ash bucket will descend to the bottom of its tower while the 35 coal bucket will ascend. When the coal bucket reaches the top of the tower, the limit switch 34 will be opened for stopping the motor.

When the motor is stopped, the coal 40 bucket will be up, and the limit switch 34 will be open. Now assuming that it is desired to hoist coal, the lever 28 will be operated to open the protective switch 30 and move the loader bar 18 to operative position. The shunt switch 55 will then be closed, and the starting switch 53 will be momentarily closed for energizing the coil 38 for closing the relay switch 39. The motor will accordingly be started again and 45 its operation will raise the ash bucket and lower the coal bucket, which will now actuate the loader bar 18 for opening the apron 21. The bucket will be coaled, hoisted and dumped into the upper hopper. It may 50 then descend for another load, the hoist being mechanically reversed, and one bucket balancing the other as they are alternately raised and lowered. If it is desired to stop the motor at any time, an emergency or stop 55 switch may be actuated.

From the foregoing, it will be apparent 60 that novel hoisting mechanism has been produced in which two buckets in different towers are alternately raised and lowered, and in which a novel control has been pro-

vided which prevents the motor from being started from the ash hoist switch until the coal loading mechanism in the coal hoist has been rendered inoperative.

I am aware that many changes may be 70 made, and numerous details of construction may be varied through a wide range without departing from the principles of this invention, and I therefore do not purpose limiting the patent granted hereon, otherwise 75 than necessitated by the prior art.

I claim as my invention:

1. In an apparatus of the class described, the combination with a pair of oppositely movable buckets, means including a motor 80 for raising and lowering said buckets, a loader mechanism controlled by one bucket, manually operated means for rendering said loader mechanism inoperative, a switch controlled by the position of said means, and a 85 control for the motor connected to said switch.

2. In an apparatus of the class described, a coal hoisting tower, a bucket in said tower, a cable attached to said bucket, a loader bar 90 normally in the path of said bucket, an ash hoisting tower, an ash bucket therein, a cable attached to said ash bucket, a drum to which said cables are attached, a motor for operating said drum, a control for said motor 95 having a switch, and means for simultaneously shifting said loader bar out of the path of said coal bucket and closing said switch.

3. In an apparatus of the class described, 100 a pair of hoisting buckets, a cable attached to each bucket, a common drum to which said cables are attached, a motor for operating said drum, loader mechanism for one bucket including a bar movable with respect to the 105 path of such bucket, and an electrical control system for the motor embodying means for preventing the motor from being operated when said loader bar is in the path of said bucket.

4. In an apparatus of the class described, 110 a coal hoisting bucket, an ash hoisting bucket, a drum, cables connecting said buckets with said drum, a motor for rotating said drum, a coal loading mechanism 115 embodying a loader bar, shiftable with respect to the path of the coal hoisting bucket, a control system for the motor embodying a pair of starting switches, one switch being effective for starting the motor when 120 the loader bar is out of the path of the coal bucket, and the other switch being effective for starting the motor when the loader bar is in operative position.

5. In an apparatus of the class described, 125 a coal hoisting tower, an ash hoisting tower, a bucket in each tower, coal loading mechanism adapted to be actuated by one bucket, means for disabling said loading mechanism, a drum, cables attaching said buckets 130

4
to said drum, a motor for operating said buckets, a drum to which said buckets are 20 connected, a loader mechanism for one bucket, means for disabling said loader mechanism, a motor for rotating said drum, and an electrical control system for the motor including a switch controlled by said 25 disabling means.

6. In an apparatus of the class described, a pair of spaced towers, a bucket in each tower, a common driving means for simultaneously raising one bucket and lowering the other, said driving means including a motor, a control system for the motor embodying a limit switch in one tower actuated by the bucket therein, for stopping the motor, said system embodying means for starting the motor when said limit switch is open.

7. In an apparatus of the class described, a pair of oppositely moving hoisting

8. In an apparatus of the class described, a pair of spaced hoisting towers, a bucket in each tower, a common drum to which said buckets are connected, means for driving 30 said drum, a movable loader mechanism for one bucket, and means controlled by said loader mechanism for controlling said driving means.

In testimony whereof I have hereunto 35 subscribed my name.

JOHN GEORGE FORSTER.
